UNITED STATES PATENT OFFICE.

JAMES SHAW, OF SAN FRANCISCO, CALIFORNIA, ASSIGNOR TO BELLE H. SHAW, OF LODI, CALIFORNIA.

MANUFACTURE OF PAPER-PULP BOTTLES AND THE LIKE.

Application filed June 24, 1926. Serial No. 118,152.

This invention relates to improvements in methods and means for manufacturing paper pulp milk bottles and the like, which have restricted neck or mouth openings which renders the use of solid and non-disintegrating cores impossible—a feature which has heretofore prevented the manufacture of such bottles in a commercially practicable manner.

10 The principal object of my invention therefore is to provide a special form of core for use in the manufacture of such bottles, a means for making the core and a means for making the bottle in connection with the core which enables the use of a solid mold for the bottle and renders it an easy matter to pour or force the pulp into the mold in order for said pulp to assume the proper bottle forming shape.

20 Generally my improvement in the manufacture of these bottles contemplates the use of a core of ice which is allowed to melt when it has served its purpose and which is made and mounted in the bottle mold, as hereinafter seen.

A further object of the invention is to produce a simple and inexpensive device and yet one which will be exceedingly effective for the purpose for which it is designed.

30 These objects I accomplish by means of such structure and relative arrangement of parts as will fully appear by a perusal of the following specification and claims.

In the drawings similar characters of reference indicate corresponding parts in the several views:

Fig. 1 is a sectional elevation of a milk bottle core-mold.

Fig. 2 is a similar view of the bottle mold showing the core mounted in the mold.

Fig. 3 is a fragmentary bottom plan view of the bottle mold cap.

Fig. 4 is a fragmentary cross section of the mold.

45 Referring now more particularly to the characters of reference on the drawings the numeral 1 denotes a flat supporting element having an upstanding circular flange 2 to removably receive and locate the lower end of the core mold 3. This mold is made of a suitable metal or other material having

50 high heat conducting properties.

The mold has a longitudinal opening 4 in the form of an inverted milk bottle, the portion of said opening which corresponds to the sides of the milk bottle having a slight diverging slope towards its upper end so that the core when formed can be readily withdrawn from the mold when the latter is inverted.

60 A cap 5 is mounted for vertical adjustment on the top of the mold and extends downwardly into the same a certain distance. The bottom of the cap has an outline corresponding to that desired for the interior of the bottom of the bottle to be formed and is so located relative to the opening 4 that the enclosed chamber thus formed in the mold is equal in size and shape to that of the interior of a standard milk bottle of certain capacity.

65 The cap has a number of vertical and small orifices 6 therethrough so that air can escape from the chamber when the water enters the same at the opposite end.

75 Mounted on the support 1 centrally of the mold is a hollow cone 7 connected to a water pipe 8 projecting upwardly from below the support. This cone is centralized relative to the lower end of the mold opening and projects upwardly into the same a certain distance. The cone has a plurality of orifices 9 leading from the pipe to the interior of the mold area.

To form the core the operations are preferably carried out in a room in which the temperature is maintained as low as is practicable and very cold water is allowed to enter the mold from the pipe 8 in such a manner as not to fill the mold chamber to the top but only to a certain level, as at A.

85 The proper volume of the water is calculated so that when expansion, due to freezing, takes place, the ice will fill the entire chamber and will take the shape of the surrounding mold walls, as well as that of the bottom of the cap 5. After the water has been poured into the mold and frozen the cap is removed from the mold and the latter is inverted so that the core may slide out. 95 The core 10 is then a solid piece of ice with a cone-shaped socket at one end corresponding to the cone 7.

100 For making the bottle I provide a verti-

cal mold 11 arranged to be removably located on a flat supporting element 12 by means of an upstanding continuous flange 13 thereon. The mold has a longitudinally extending opening 14 therein, tapered toward its upper end to correspond to the taper of the core. At the upper end of said opening a hollow cap 15 is fitted onto the mold. The chamber in the mold thus formed by the side walls and the cap and extending between said cap and the lower end of the mold is symmetrical to the core 10 but larger, being of a size equal to the exterior contour of the bottle to be formed. The cap 15 has a plurality of small concentric grooves 16 in its lower face, from which grooves small holes 17 lead into the enclosed chamber 18 formed in the cap.

Mounted on the support 13 centrally of the mold is a circular flange member 19 whose diameter is intermediate the exterior and interior diameter of the bottle at the mouth, and which projects somewhat above the level of the support 13 on which the mold rests. Projecting upwardly and centrally from said flange is a cone 20, exactly the same size as the cone 7 of the core mold. The cone and flange are connected to a pipe 21 through which the pulp is fed from a suitable source of supply, radial holes 22 leading from the pipe to the rim of the flange. The opening 14 in the bottle mold preferably has a large number of small vertical grooves down its sides from the cap 15 to the bottom of the mold, said grooves being shown in exaggerated form at 23 in Fig. 4. In operation the core having been made the cap 15 of the bottle mold is removed and the core 10 is inserted.

The socket in the core fits over the cone 20 so that the core is centrally located in the mold 11 relative to the opening 14 and of course is spaced from the sides of said opening as well as from a cap 15 a certain distance. A space all around the core is therefore formed in the bottle mold, the width of this space determining the thickness of the bottle. Pulp of a suitable character and also maintained at a low temperature is then forced upwardly through the pipe 21 and into said space through the openings 22 to form the bottle 24. The air displaced from the mold space with the advancing pulp passes into the chamber 18 of the cap, being there compressed to a certain extent. The pressure on the incoming pulp being greater than that of this confined air, water from the pulp is also forced into the chamber 18. The pulp being of a fibrous nature will not however pass through the small holes 17 nor lodge in the grooves 16, but will lie across the same. The result is that the majority of the water in the pulp mixture will be immediately drained from

the same, leaving the pulp in the mold-space 65 in a firm condition.

Should the holes 17 tend to become clogged, an intermittent slackening-up action on the pulp pressure will cause the air pressure to act to blow through and unclog 70 the holes, as will be evident.

The grooves 16 aid in carrying off the water from the pulp into the holes 17 while the vertical grooves 23 (which are arranged to connect with the outermost groove 16) 75 drain the water from the sides of the bottle, these grooves being so small that the pulp will merely lie across the same. Owing to the flange 19, when the bottle is formed a circular depression around the inside of the 80 mouth of the bottle will be provided to receive the usual cover cap.

When the bottle has been completely poured the mold is removed from the support and inverted. The water in the cap will then 85 drop to the bottom of the chamber 18, and the cap is then removed. The mold is then placed in a warm room so that the core will melt and flow out, when the bottle may be withdrawn from the mold.

From the foregoing description it will be readily seen that I have produced such a device as substantially fulfills the objects of the invention as set forth herein.

While this specification sets forth in detail 95 the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A method of making a paper pulp vessel in a mold consisting in placing in the 105 mold chamber, a core made of ice, pouring the pulp into the mold around the core, and allowing the core to melt.

2. In combination, a mold having an interior chamber whose area and shape is that 110 of the interior of a vessel to be made, and an ice core to fit in said chamber in spaced relation to the walls thereof.

3. In combination, a mold having an interior chamber whose area and shape is that 115 of the interior of a vessel to be made, said chamber being open on its lower end, a member on which said mold removably rests, a cone projecting upwardly from the support into the lower end of the chamber, and a 120 core to fit into the mold chamber in spaced relation to the wall thereof, the core being formed with a socket in the corresponding end to fit over said cone.

4. A method of making a pulp vessel in a 125 mold consisting in placing in the mold chamber, a core made of a solid but meltable substance, pouring the pulp into the mold

around the core, and then allowing the core to melt.

5. In combination, a vertical mold having a longitudinal chamber open on its upper end, a cap having a plurality of perforations therethrough to fit in the top of the mold, a core to fit in the mold chamber in spaced relation to the side-walls and cap,

and means for introducing pulp into the space between the core and mold at the bottom of the latter, the inner walls of the mold having longitudinal grooves leading from the bottom to the cap. 10

In testimony whereof I affix my signature.

JAMES SHAW.
